UNITED STATES PATENT OFFICE.

EDWIN L. WHITE, OF BROOKLYN, NEW YORK.

DESIGN FOR A HANGER FOR LIGHT-TRANSMITTING BOWLS.

52,000.

Specification for Design. Patented Apr. 30, 1918.

Application filed February 20, 1918. Serial No. 218,375. Term of patent 7 years.

To all whom it may concern:

Be it known that I, EDWIN L. WHITE, a citizen of the United States, residing at the borough of Brooklyn, in the county of Kings, city and State of New York, have invented a new, original, and ornamental Design for a Hanger for Light-Transmitting Bowls, of which the following is a specification, reference being had to the accompany drawing, forming a part thereof.

Figure 1, is a front elevation of a hanger for light transmitting bowls, showing my new design, and

Fig. 2, is a side elevation of the same.

I claim:

The ornamental design for a hanger for light transmitting bowls, as shown.

EDWIN L. WHITE.
